HEDGE SHEARS

Lars Hedstrom, Mendham, N.J., assignor to J. Wiss & Sons Co., Newark, N.J., a corporation of New Jersey

Filed May 4, 1962, Ser. No. 69,974

Term of patent 14 years

(Cl. D22—4)

FIG. 1 is a front elevational view of a pair of hedge shears showing my new design;

FIG. 2 is an enlarged (rear or front) elevational view of one of the handles thereof, the broken line portions of the shears being omitted for convenience of illustration;

FIG. 3 is a side elevational view thereof; and

FIG. 4 is a top plan view of the handle shown in FIG. 1, slightly enlarged.

The essential features of the design are depicted in full lines and reside in the particular handle members which are beveled and shaped as shown.

I claim:

The ornamental design for hedge shears, as shown and described.
